United States Patent Office

Des. 233,847

Patented Dec. 3, 1974

233,847

TOY SHOOTING GALLERY

Raymond J. Lohr and Martin Condry, Erie, Mahlon E. Hirsch, Fairview, and Laurie Jay Campbell and Maxmillian P. Rogers, Erie, Pa., assignors to Louis Marx & Co., Inc.

Filed May 29, 1973, Ser. No. 364,578

Term of patent 14 years

Int. Cl. D21—01

U.S. Cl. D34—5 PP

FIG. 1

FIG. 2

FIG. 3

FIG. 4

FIG. 5

FIG. 1 is a front perspective view of a toy shooting gallery showing our new design;

FIG. 2 is a side elevational view thereof;

FIG. 3 is a front elevational view thereof;

FIG. 4 is a bottom plan view thereof taken along the line 4—4 of FIG. 2; and

FIG. 5 is a rear elevational view thereof taken along the line 5—5 of FIG. 2.

We claim:

The ornamental design for a toy shooting gallery, as shown.
